UNITED STATES PATENT OFFICE.

EDWARD T. SPILLMAN, OF COLUMBUS, OHIO, ASSIGNOR TO THE V-W VENTILATOR CO., OF COLUMBUS, OHIO.

VENTILATOR.

Application filed May 15, 1923. Serial No. 639,154.

To all whom it may concern:

Be it known that I, EDWARD T. SPILLMAN, a citizen of the United States of America, residing at Columbus, in the county of 5 Franklin and State of Ohio, have invented certain new and useful Improvements in Ventilators, of which the following is a specification.

My present invention relates generally to ventilators and more particularly to roof ventilators, my primary object being the provision of a ventilator of this type which will work automatically and continuously in an effective efficient manner 15 with free full outlet for the internal currents and without back pressure irrespective of the velocity and direction of the external currents.

A further object is the provision of a ventilator of this type, the construction of 20 which insures strength and durability and avoids the necessity of all moving parts and wear, rattling and squeaking ordinarily incident thereto.

25 A still further object is the provision of a roof ventilator whose initial cost is low, whose construction obviates the necessity for power, and whose upkeep is therefore practically without expense.

30 The preferred embodiment of my invention is shown in the accompanying drawing and the further objects as well as the resulting advantages of my invention will be better understood from the following description by reference to the several figures of the drawing, which forms a part of this specification and in which—

Figure 1 is a side elevation of my improved ventilator,

40 Figure 2 is a sectional top plan view thereof taken substantially on line 2—2 of Figure 1,

Figure 3 is a vertical section taken diametrically therethrough,

45 Figure 4 is a horizontal section taken substantially on line 4—4 of Figure 1,

Figure 5 is a detail radial section taken substantially on line 5—5 of Figure 2,

50 Figure 6 is a detail perspective view of one of the shields, and

Figure 7 is a detail vertical section through the upper portion of the body and the shield holding ring, illustrating one of the attaching brackets for supporting a 55 ring.

Referring now to these several figures and particularly to Figures 1 to 5 inclusive I have shown my improved ventilator made up of a vertical cylindrical body 10 at spaced points around which are secured the lower 60 portions of a circumferential series of wing plates 11, these plates being disposed vertically with their upper portions projecting substantially above the upper edge 12 of the body 10 so as to form between these upper 65 standing upper portions of the wing plates a series of outlet spaces which open laterally into the upper portions of a series of circumjacent shields 13.

Above the body 10, a hood 14, preferably 70 of the shallow conical form shown, is mounted in spaced relation to the upper ends of the wing plates 11, this hood being flanged as at 15 and supported by brackets 16 which depend therefrom and are secured to the 75 upper portions of the wing plates 11, it being noted that the hood not only overlies the upper end of the body 10 but outstands therearound and beyond the wing plates 11 and also the shields 13.

The several wing plates 11 and shields 13, it will be noted, are in overlapping relation circumferentially around the body 10, the wing plates 11 having along their vertical side edges outstanding flanges 17 wider 80 at their lower ends than at their upper ends and gradually tapering as shown between these ends. The shields 13 on the other hand have along their vertical side edges inturned flanges 18 spaced from one another 85 and from the flanges 17 of the wing plates which they overlap, so as to form vertical air channels 19 between the side flanges 18 of each shield 13 and the side flanges 17 of adjacent wing plates 11 upon opposite 90 sides of said shield and so as to form larger air channels 20 within each shield 13 and between the side flanges 17 of adjacent wing plates 11, into the latter and larger channels of which the outlet spaces above the upper 95 edge of the body 10 and between the several wing plates 11 directly open.

By virtue of the tapering of the flanges 17 and 18 of the wing plates 11 and the shields 13 it is obvious that provision is made for 100 the passage of air circumferentially between the upper portions of the several vertical air channels 19 and 20 and by reference to Figure 1 it will be noted that the flanges 18 of the shields 13 are secured at their ex- 110

treme lower ends as by means of rivets and like fastening members 21 to the lower portions of the wing plates 11.

The upper ends of the several shields 13 are secured by rivets or like fastening members to a supporting ring 22, this ring being secured in spaced relation around the upper portions of the several wing plates 11 by angular brackets 23 secured at their outer 10 portions to the ring and at their inner portions to the upper ends of the wing plates so that it is thus obvious the entire structure is a rigid assembly of stationary metal parts whose interconnection and cooperative relation brings about the desired result without necessitating moving parts and the requirement for power in the operation of such parts and thus avoids the wear, rattling and squeaking ordinarily incident to the presence of moving parts.

The relation in connection with the several parts in the rigid assembly shown and described furthermore brings about a circumferential series of vertical air channels around the body which, like the body itself, open beneath the hood and which are so formed that provision is made for their intercommunication circumferentially around the body so that irrespective of the direction or the velocity of the outside air currents, full free outlet of internal currents is provided for at all times without danger of interference as for instance by back pressure.

38 My improved ventilator involving as it does a rigid assembly of parts which may be stamped from sheet metal, may be produced at an initial low cost and, in view of the above it is obvious that in use it will be 40 strong and durable and practically without cost of upkeep.

I claim:

1. A ventilator of the type described including a vertical cylindrical body, a series 45 of wing plates disposed vertically around and projecting above the body to form laterally opening outlet spaces between their upper portions, said wing plates having radially outstanding side flanges, a series of 50 shields around and spaced from the body opposite the said outlet spaces between the wing plates and overlapping the said wing plates, having inturned vertical side flanges spaced from one another and from the wing 55 plate flanges to form vertical air channels around the body between the several flanges, and a hood spaced above the upper end of the body and the upper ends of said wing plates and shields, below which the upper 60 ends of the said air channels open as described.

2. A ventilator of the type described including a vertical cylindrical body, a series of wing plates disposed vertically around and projecting above the body to form laterally opening outlet spaces between their upper portions, said wing plates having radially outstanding side flanges, a series of shields around and spaced from the body opposite the said outlet spaces between the wing plates and overlapping the said wing plates, having inturned vertical side flanges spaced from one another and from the wing plate flanges to form vertical air channels around the body between the several flanges, and a hood spaced above the upper end of the body and the upper ends of said wing plates and shields, below which the upper ends of the said air channels open, the said flanges of the wing plates and the shields tapering from relatively wide lower ends to relatively narrow upper ends as and for the purpose set forth.

3. A ventilator of the type described including an upright hollow body, a hood spaced above said body and outstanding therearound, and means forming a series of vertical air channels around the body and opening upwardly beneath the hood, consisting of a circumjacent series of inner and outer flanged members in alternating circumferentially overlapping relation, the flanges of which are spaced from one another; said inner members being fixed to the said body, and a ring supported by the upper ends of said inner members and to which the outer members are connected.

4. A ventilator of the character described including an upright hollow body, a hood spaced above said body and outstanding therearound, a series of vertical plates secured to and extending above the body at spaced points therearound and having outstanding vertical side flanges, a second series of plates between and overlapping the plates of the first series and having inturned vertical side flanges spaced from one another and from the side flanges of the first series of plates, said second series of plates being rigidly secured at the lower ends of their flanges to the plates of the first series and to the body and having their upper ends beneath the outstanding portion of the hood, a supporting ring to which the upper ends of the plates of the second series are connected, and brackets rigidly connecting said ring at spaced points with the upper ends of the plates of the first series as described.

In testimony whereof I have affixed my signature.

EDWARD T. SPILLMAN.
